FIGURE 1 is an elevational view of a container for oil products or the like showing our new design wherein the container has a ribbed columnar section including a non-ribbed area for product identification;

FIGURE 2 is a top view thereof;

FIGURE 3 is a bottom view thereof;

FIGURE 4 is an elevational view of a modified container for oil products or the like wherein the columnar section has a greater ribbed area than that of the container of FIGURE 1; and

FIGURE 5 is an elevational view of another modified container for oil products or the like wherein the columnar section contains a greater ribbed area than that of the container of FIGURE 4.

The top and bottom views for the containers of FIGURES 4 and 5 are the same as those shown in FIGURES 2 and 3.

We claim:

The ornamental design for a container for oil products or the like, substantially as shown and described.
